UNITED STATES PATENT OFFICE.

FREDERICK G. CRABB, OF NEW HAVEN, CONNECTICUT, ASSIGNOR TO INSULL & CRABB,
A FIRM COMPOSED OF JOHN C. INSULL AND FREDERICK G. CRABB.

DESIGN FOR A BADGE, EMBLEM, OR SIMILAR ARTICLE.

51,010.

Specification for Design.

Patented July 10, 1917.

Application filed May 10, 1917. Serial No. 167,829. Term of patent 3½ years.

To all whom it may concern:

Be it known that I, FREDERICK G. CRABB, a citizen of the United States, residing at New Haven, in the county of New Haven and State of Connecticut, have invented a new, original, and ornamental Design for a Badge, Emblem, or Similar Article, of which the following is a specification, reference being had to the accompanying drawing, forming part thereof.

The figure is a face view of a badge, emblem, or similar article, showing my new design.

I claim:

The ornamental design for a badge, emblem, or similar article, as shown.

FREDERICK G. CRABB.

Witnesses:

FREDERIC C. EARLE,
M. P. NICHOLS.
